UNITED STATES PATENT OFFICE.

RASCO DIXON, OF FAUNSDALE, ALABAMA.

FIREPLACE UNIT.

Application filed April 29, 1926. Serial No. 105,490.

My present invention has to do with fireplaces; and it contemplates the provision of a fireplace unit, or one piece device, adapted to be handled with facility as such and placed as one piece in and removed as one piece from a fireplace; the said device being adapted to be produced with facility and being simple and inexpensive in construction and in general well adapted to withstand the usage to which fireplace appurtenances are ordinarily subjected.

With the foregoing in mind, the invention in all of its details will be fully understood from the following description and claim 15 when the same are read in connection with the drawings, accompanying and forming part of this specification in which:—

Figure 1 is a front elevation of the fireplace unit constituting the preferred embodiment of my invention.

Figure 2 is a horizontal section, taken in the plane indicated by the line 2—2 of Figure 3, looking downwardly.

Figure 3 is a vertical central section of the unit.

Similar numerals of reference designate corresponding parts in all of the views of the drawings.

Among other elements my novel fireplace unit comprises a front portion 1 of general inverted U-shape, and a grate 2, the said front portion 1 and the grate 2 being preferably cast in one piece, and the material employed being preferably cast iron. It will be noticed in this connection that the grate 2 has an open work front portion and an open work bottom portion, and on the rear of the said bottom portion are supporting legs 3, one at each end of the grate.

In addition to the front portion 1 and the grate 2 characterized as described, the fireplace unit comprises a U-shaped frame 4 disposed back of the front portion 1 and bolted thereto at 5, and a casing cast in one piece of iron with the said frame 4, the said casing having a back wall 6, and also having side walls 7, the latter extending from the frame 4, and the upper ends of the back wall 6 and the side walls 7 being flared as designated by 6^x and 7^x, respectively.

It will be apparent from the foregoing that in the manufacture of my novel grate unit, the front portion or frame 1 and the

grate 2 are produced separately from the back wall 4 and the casing integral with the back wall 4, after which the said sections or parts are relatively arranged as shown and are fixedly connected in such relative arrangement through the medium of bolts 5, rivets or other devices extending through the front frame or portion 1 and the back frame or portion 4.

My novel fireplace unit is designed more especially for use in fireplaces of country homes, and it will be appreciated from the foregoing that my novel fireplace unit is adapted to be expeditiously and easily placed in a fireplace so that coal of appropriate type may be used as fuel, and that when occasion demands my novel fireplace unit may as readily be removed from the fireplace.

It will also be apparent from the foregoing that my novel fireplace unit is simple and inexpensive in construction and is well adapted to withstand rough usage and intense heat.

I have specifically described the preferred embodiment of my invention in order to impart a full, clear and exact understanding of the same. I do not desire, however, to be understood as limiting myself to the precise construction and relative arrangement of parts as disclosed, my invention being defined by my appended claim within the scope of which modifications may be made without departure from my invention.

Having described my invention, what I claim and desire to secure by Letters-Patent, is:—

A fireplace unit comprising a front portion or frame of inverted U-shape, a great integral with said front portion or frame and having an open work front and also having an open work bottom and legs on the rear portion of said bottom, a frame of inverted U-shape arranged back of and connected to the first named portion or frame of inverted U-shape, and a casing integral with the back frame and containing the grate and having a back wall and also having side walls.

In testimony whereof I affix my signature.

RASCO DIXON.
